UNITED STATES PATENT OFFICE.

FRANK TOCKES, OF CHICAGO, ILLINOIS.

DESIGN FOR A CHEST.

59,614.

Specification for Design.

Patented Nov. 8, 1921.

Application filed February 26, 1921. Serial No. 448,245. Term of patent 7 years.

To all whom it may concern:

Be it known that I, FRANK TOCKES, a citizen of Austria-Hungary, residing at Chicago, in the county of Cook and State of Illinois, have invented a new, original, and ornamental Design for Chests, of which the following is a specification, reference being had to the accompanying drawing, forming part thereof.

The figure is a perspective view of a chest, showing my new design.

I claim:

The ornamental design for a chest, as shown.

FRANK TOCKES.
